The diagram illustrates a mechanical assembly, likely a steering linkage, with the following components labeled:

- FORWARD**: An arrow pointing to the left, indicating the forward direction.
- 65**: A horizontal rod extending from the left.
- 33**: A vertical rod connected to the end of 65.
- 34**: A horizontal rod connected to the end of 33.
- 29**: A vertical rod connected to the end of 34.
- 35**: A horizontal rod connected to the end of 29.
- 46**: A horizontal rod connected to the end of 35.
- 61**: A vertical rod connected to the end of 46.
- 26**: A vertical rod connected to the end of 61.
- 24**: A vertical rod connected to the end of 26.
- 23**: A vertical rod connected to the end of 24.
- 12**: A vertical rod connected to the end of 23.
- 11**: A large circular wheel or hub.
- 22**: A vertical rod connected to the side of 11.
- 47**: A vertical rod connected to the end of 22.
- 55**: A vertical rod connected to the end of 47.
- 51**: A horizontal rod connected to the end of 55.
- 52**: A vertical rod connected to the end of 51.
- 42**: A horizontal rod connected to the end of 52.
- 27**: A vertical rod connected to the end of 42.
- 19**: A vertical rod connected to the end of 27.
- 18**: A horizontal rod connected to the end of 19.
- 56**: A horizontal rod connected to the end of 18.
- 59**: A vertical rod connected to the end of 56.
- 58**: A horizontal rod connected to the end of 59.
- 72**: A vertical rod connected to the end of 58.
- 15**: A vertical rod connected to the end of 72.
- 70**: A horizontal rod connected to the end of 15.
- 17**: A vertical rod connected to the end of 70.
- 71**: A vertical rod connected to the end of 17.
- 14**: A vertical rod connected to the end of 71.
- 16**: A vertical rod connected to the end of 14.

A detailed view on the right shows a rectangular frame with internal components labeled 15, 70, 17, 71, 14, and 16, corresponding to the main assembly.

ENGINE SHAFT ACTUATED LOCOMOTIVE
VALVE GEAR OF THE SUSPENDED EC-
CENTRIC ROD TYPE

Samuel D. Dekle, Atlantic Beach, Fla.

Application May 10, 1944, Serial No. 534,859

11 Claims. (Cl. 121—169)

1

This invention relates to valve gears and, more particularly, to such for operating a locomotive.

The principal object of my invention, generally considered, is to provide a steam-engine valve gear of improved construction and operation.

Another object of my invention is to provide a valve gear which requires only a small amount of lap to obtain perfect valve events, as compared to the larger valve laps of other types of gear, thereby cutting down excessive wearing of valves and bushings, especially when in running cut-off.

A further object of my invention is to provide a valve gear that gives a greater amount of starting power when obtaining full valve travel by quickly opening the steam port at the beginning of the piston stroke and delaying closing of the exhaust port when the piston is nearing completion of its stroke.

A still further object of my invention is to provide a valve gear in which the wearing points are greatly reduced, as by the elimination of combination levers and union links.

An additional object of my invention is to provide a light-weight gear which is readily accessible and which is provided with a self-aligning bushing in the back end of the combination eccentric blade, thereby eliminating side stress and strain to the blade, due to lateral motion in the driving wheels.

Another object of the valve gear is to satisfactorily allow for the fall and rise of the engine frame when going around curves, by making the valve gear eccentric rod ratio large, that is, sixteen to one.

Other objects and advantages of the invention, relating to the particular arrangement and construction of various parts, will become apparent as the description proceeds.

Referring to the drawing illustrating my invention,

Figure 1 is a side elevation of the forward parts of the running gear of a steam locomotive, including one embodiment of my improved valve gear.

Figure 2 is a fragmentary plan of the gear and associated parts shown in Figure 1.

Figure 3 is a vertical sectional view on the line III—III of Figure 1, in the direction of the arrows, the gear, however, being shown in neutral position, as illustrated diagrammatically in Figure 8.

Figure 4 is a diagrammatic illustration of the gear when the reversing mechanism is in full

forward position and the main crank in its forward dead center position.

Figure 5 is a view corresponding to Figure 4, but showing the positions of the parts when the main driver has turned 90° in moving forward.

Figure 6 is a view corresponding to Figure 5, but showing the positions of the parts when said driver has turned another 90° forward.

Figure 7 is a view corresponding to Figure 6, but showing the positions of the parts when the driver has turned still another 90° in moving forward.

Figure 8 is a diagrammatic illustration of the gear when the reversing mechanism is in neutral or running cutoff position, the full line positions of the gear otherwise corresponding with Figure 7, and the dotted line positions attempting to show the positions of the parts when the main driver is in the angular positions represented by Figures 4, 5 and 6.

Figure 9 is a view corresponding to Figure 8, but showing the positions of the parts when the reverse mechanism is positioned for full travel reverse operation.

Figure 10 is a valve ellipse or displacement curve for a valve gear embodying my invention.

Referring to the drawings in detail, like parts being designated by like reference characters, and first considering Figures 1, 2 and 3, it will be seen that I have illustrated one embodiment of my invention as applied to a steam locomotive having on each side, only one of which is illustrated, a forward driving wheel 11 and a main driving wheel 12. Said wheels are journaled with respect to a locomotive frame 13 carrying a cylinder 14 with a steam chest 15. In the cylinder reciprocates a driving piston 16 and in the steam chest is a piston valve 17, illustrated only in the diagrammatic views of Figures 4 to 9 inclusive.

The piston 16 has a rod 18 connected to a cross head 19 slidable on a guide 21 and to which is pivoted a connecting rod 22, the other end of which is pivoted to the main crank pin 23 of the driver 12. An eccentric crank 24 is attached to a preferably axial extension 25 on the main crank pin 23 and preferably set so that its free end trails the movement of the main crank pin 90° when the drivers are moving forward.

To the free end of the eccentric crank is pivoted the eccentric rod or blade 26, the forward or free end of which is, in turn, pivotally carried by radius arms 27 and 28. The upper ends of the radius arms are connected to intermediate portions of a reversing member or yoke 29, as by

pivot pins 31 and 32, respectively, as shown most clearly in Figure 3.

The reverse yoke 29 is part of the reversing mechanism for the gear. Its upper portion is bifurcated to straddle the forward end of a reach rod 33 and it is connected thereto by pivot pin 34.

The lower portion of the yoke 29 is also bifurcated and straddles a link block 35 which is slideable in an arcuate link or segment 36, said block being connected to the yoke 29 by a pivot pin 37. The link 36 is mounted on the top of a gear frame 38, in turn carried by the main locomotive frame 13. The lower bifurcated portions of the yoke 29 are each, in turn, bifurcated and straddle outer and inner elements 39 and 41 of the frame 38, and their lower ends carry generally rectangular blocks 42 and 43 by means of pivot pins 44 and 45, said blocks being adapted to reciprocate vertically with respect to said frame 38 as the yoke is moved by the reach rod 33.

The rise and fall of the lower ends of the reverse yoke is accounted for by the fact that the link slot 46 in which the block 35 moves has a radius of curvature (in the embodiment illustrated 37 $\frac{1}{4}$ ") which is longer than the distance between the block 35 and the line passing through the axes of the pivot pins 44 and 45 (in the embodiment illustrated 26"). This reciprocation movement is provided to insure the desired sequence of valve events. In the embodiment illustrated these blocks reciprocate $\frac{1}{2}$ of an inch, thereby allowing the reverse yoke to give the correct radius through the radius arms to the front end of the eccentric rod or blade.

The gear frame 38 also carries a bell crank 47 comprising an elongated hub portion 48 mounted between the elements 39 and 41 of the gear frame 38 as on pivot pin 49. From the hub 48 projects an arm 51 in a generally forward, horizontal direction and the forward end of which is straddled by a transmission link 52 to which it is connected as by means of pivot pin 53.

The lower end of the transmission link is also bifurcated and straddles a portion of the eccentric rod 26 intermediate the ends but near the connection with the radius arms 21 and 28, being connected thereto as by means of pivot pin 54.

The other bell crank arm 55 depends from the hub 48 and is desirably bifurcated, straddles, and is connected to the rear end of, a valve rod 56, as by pivot pin 57. The front end of the valve rod is connected to the valve cross head and valve stem 58 by means of pivot pin 59.

The reverse yoke 29 is operated to vary the cut-off provided by the gear and for the reversal of the direction of travel, as desired, by the reach rod 33, the rear end of which is connected to the outer crank 61 of a reversing shaft 62, as by means of pivot pin 63, and the inner crank 64 of which is connected to the front end of reversing shaft 65, as by pivot pin 66. The reversing shaft is, in turn, manually operable as by means of reversing lever 67 to which it is connected, as by means of pivot pin 68.

Referring now to the diagrammatic representation in Figure 4, it will be seen that, when the piston 16 is in forward dead-center position, the rear end of the eccentric rod 26 is disposed 90° behind the crank-connected end of the rod 22 so that, when the reversing mechanism is in the forward corner, as illustrated in Figure 1, the valve 17 is just starting to admit steam, represented by the arrow 69 in Figure 4, from the live steam compartment 70 of the chest 15 through port 71 in front of the piston 16, the rear portion

of said valve 17 having opened port 72 to exhaust and so as to avoid back pressure. This position corresponds with the point 73 on the valve ellipse of Figure 10.

Figure 5 shows the relative positions of the valve gear parts when the drive wheel 12 has moved forward through an angle of 90°. During this movement the piston 16 has moved approximately half of its stroke or to a point designated 10 by the reference character 74 in Figure 10. At the same time, the valve as shown has completely opened the port 71 and is starting to close it. In other words, the valve, during this 90° movement, has advanced from a slight opening of the steam port to beyond the full opening thereof.

Figure 6 shows the position of the parts while the locomotive is moving forward, but with the crank in rear dead-center position. During this movement from Figure 5 to Figure 6 cut-off has occurred, as designated by the reference character 75 in Figure 10, followed by release, designated by reference character 76 in Figure 10, upon opening of the port 71 to the exhaust chamber 77. Figure 6, therefore, corresponds with Figure 25 4, except that steam, represented by the arrow 78, is here just being admitted to the rear of the piston 16, with the forward end of the cylinder open to exhaust, the point on Figure 10 corresponding with this position being designated by 30 the reference character 79.

Figure 7 shows the succeeding position of the mechanism in which the driver 12 has turned through another 90° in a forward direction, in which position the port 72 is fully open to admit 35 steam back of the piston 16, exhaust taking place through port 71 to exhaust chamber 77 in front of said piston, corresponding generally with position 81 on the valve ellipse diagram of Figure 10. It will therefore be seen that Figure 7 corresponds with Figure 5, except that the directions 40 of motion of the valve and piston are reversed and the position of the valve is at approximately the opposite end of the valve chamber.

Figure 8 combines the positions of Figures 4 to 7, inclusive, for the gear when the reverse mechanism is in neutral or what might be designated as running cut-off position, that is, with the gear set for minimum steam consumption or earliest possible cut-off. This is represented by 45 the thinnest ellipse, marked 82, in the diagram of Figure 10, the point 73 on said ellipse corresponding with the setting when the rear end of the eccentric rod is positioned at 83 in forward travel. The point 84 on said ellipse 82 shows the 50 cut-off which in the embodiment illustrated is at about 44.2% of the stroke. When the driver moves through 90° to place the rear end of the eccentric rod at point 85, the position of the gear in Figure 10 is represented at 86 or during the 55 expansion of the steam after cut-off. The next point 87, representing the position of the rear end of the eccentric rod after another movement of 90°, is shown in Figure 10 by the reference character 79, and the full line position of the gear 60 is represented on Figure 10 by the reference character 88.

Figure 9 corresponds with Figure 8, except that the positions of the parts are shown for full reverse motion. Reference character 89 shows the 65 position of the rear end of the eccentric rod when the mechanism is otherwise as in Figure 7, and the characters 91, 92 and 93, respectively, show the positions of the rear end of the eccentric rod when the mechanism is otherwise as in Figures 6, 5 and 4.

The points on Figure 10 on the rearward motion valve ellipse 94 which correspond, respectively, with points 91, 92, 93 and 89 are 79, 95, 73 and 96.

From the foregoing disclosure, it will be seen that I have provided a valve gear which operates solely from a single connection with the main crank pin, the adjustment of the cut-off and reversal thereof being accomplished by a yoke mounted on a frame and carrying the front end of the eccentric rod on radius arms, pivot friction being thereby substituted, in almost all instances, by sliding friction, and all parts of the gear being conveniently accessible for lubrication and maintenance.

The valve ellipse illustrated in Figure 10 shows that the events of port opening, cut-off, release and compression occur when the valve is relatively remote from its dead center and, therefore, moving at relatively great speed. This means that these events occur quite quickly, thereby improving the power output of the locomotive by promptly admitting steam to the cylinder and cutting it off without appreciable wire drawing.

A consideration of Figure 10 will also show that the valve ellipses are substantially symmetrical, particularly for forward travel, that great economy in the use of steam may be accomplished in running cut-off and positions adjacent thereto, and all of these advantages are obtained when using a very small lap, which, in the embodiment illustrated, is $\frac{3}{4}$ of an inch, the exhaust lap being negative, that is, amounting to a clearance of $\frac{3}{16}$ of an inch.

The following table shows various features of one embodiment of my gear, having 28" cylinders, $\frac{7}{32}$ " lead, and $6\frac{5}{8}$ " valve travel when moving forward:

Cut-off, per cent	Cut-off, inches		Release, inches		Compression, inches		
	Front	Back	Front	Back	Front	Back	
44.2	12 $\frac{1}{4}$	12 $\frac{1}{4}$	19 $\frac{3}{4}$	19 $\frac{1}{16}$	41 $\frac{1}{16}$	41 $\frac{9}{16}$	
93.1	26 $\frac{3}{16}$	25 $\frac{3}{16}$	27 $\frac{7}{32}$	26 $\frac{5}{16}$	9 $\frac{1}{16}$	8 $\frac{3}{16}$	Full forward motion.
93.2	26 $\frac{3}{16}$	27 $\frac{7}{32}$	27 $\frac{7}{16}$	26 $\frac{3}{16}$	9 $\frac{1}{16}$	8 $\frac{3}{16}$	Full backward motion.

Cut-off, per cent	Preadmission, inches		Steam port, inches		Exhaust port, inches		
	Front	Back	Front	Back	Front	Back	
44.2	1 $\frac{1}{16}$	$\frac{9}{16}$	2 $\frac{7}{64}$	2 $\frac{7}{64}$	1 $\frac{1}{16}$	1 $\frac{1}{16}$	
93.1	$\frac{3}{32}$	$\frac{1}{16}$	2 $\frac{7}{8}$	2 $\frac{5}{64}$	3 $\frac{3}{16}$	3 $\frac{3}{16}$	Full forward motion.
93.2	$\frac{3}{32}$	$\frac{1}{16}$	2 $\frac{7}{16}$	3 $\frac{1}{8}$	4 $\frac{1}{16}$	3 $\frac{3}{8}$	Full backward motion.

The above data were obtained with a gear having 28" stroke, 12" eccentric crank radius, and 37 $\frac{1}{4}$ " link radius. The length between end pivots of the gear parts were: eccentric rod, 79 $\frac{5}{8}$ "; transmission link, 32 $\frac{3}{4}$ "; arm of bell crank to which connected, 8 $\frac{1}{2}$ "; valve rod, 63 $\frac{1}{2}$ "; arm of bell crank to which connected, 11 $\frac{3}{4}$ "; radius arms, 32"; reverse yoke, 33 $\frac{1}{4}$ "; distance from radius arms connecting points: (1) to link block, 10"; (2) to yoke blocks, 16".

The distance on the eccentric rod between the points of connection with the transmission link and with the radius arms was 4 $\frac{3}{8}$ ". This means that said distance is about, but less than, $\frac{1}{16}$ of the distance from the transmission link connection with the eccentric rod to the eccentric crank

connection therewith. Thus the fall and rise of the engine frame when going around curves is satisfactorily allowed for, as when the reverse yoke is positioned for full forward or reverse travel, the ratio in relation to the main crank pin is approximately 16:1. In other words, a vertical movement of the frame of even as much as one inch with respect to the wheels, as upon rounding a curve, involves a relative movement of the transmission link 52 of only about $\frac{1}{16}$ inch, so that the corresponding valve movement is minimized, as contrasted with that in the Brown Patent No. 1,076,406, for example, in which the ratio is apparently less than 7:1.

Although a preferred embodiment of my invention has been disclosed, it will be understood that modifications may be made within the spirit and scope of the appended claims.

I claim:

1. In a steam-engine valve gear, in combination with a frame, a main crank pin and a valve, an eccentric rod, one end of which is pivoted with respect to a point substantially 90° out of phase, but movable with said crank pin, reversing mechanism to which the other end of said rod is pivoted to cause it to swing in an arc about a center determined by the setting of said mechanism, said mechanism comprising a reverse yoke carrying a block slidable in a link fixed to the top of said frame, said yoke having normally depending end portions carrying blocks vertically reciprocable in said frame, radius arms the upper ends of which are pivotally carried by intermediate portions of said yoke and the lower ends of which are pivotally connected to the free end of said eccentric rod, a bell crank lever pivoted to said frame, a transmission link connecting one arm of said lever to an intermediate portion of said eccentric rod, and a valve rod con-

necting another arm of said lever to said valve, to operate the latter.

2. In a steam-engine valve gear, in combination with a gear frame, a main crank pin and a valve, an eccentric crank secured to said pin and with its free end trailing it 90° in forward motion, an eccentric rod, one end of which is pivoted to said free crank end, reversing mechanism comprising an arcuate link fixed to said frame, a reversing member, a block carried thereby and slidable in said link, means for moving said member, a link movably supporting the other end of said rod from a part of said reversing member below said block, a bell crank lever, pivoted to said frame, a transmission link connecting one arm of said lever to an intermediate

portion of said eccentric rod, and a valve rod connecting another arm of said lever to said valve, to operate the latter.

3. In a steam-engine valve gear, in combination with a frame, a main crank pin and a valve, an eccentric rod, one end of which is pivoted with respect to a point substantially 90° out of phase but movable with said crank pin, a reverse yoke, a link fixed to the top of said frame, a block carried by said yoke and slidable in said link, said yoke having normally depending end portions carrying blocks vertically reciprocable in said frame, radius arms, the upper ends of which are pivotally carried by intermediate portions of said yoke and the lower ends of which are pivotally connected to the free end of said eccentric rod, a bell crank lever pivoted to said frame, a transmission link connecting one end of said lever to an intermediate portion of said eccentric rod, and a valve rod connecting another arm of said lever to said valve, to operate the latter.

4. In a steam-locomotive valve gear, in combination with a frame, a main crank pin and a valve, an eccentric rod, one end of which is pivoted with respect to a point substantially 90° out of phase, but movable with said crank pin, a reversing member having a lower end portion movably connected to said frame, and an upper end portion, operating means connected to said upper end portion, link means connecting the other end of said rod to said member intermediate said upper and lower end portions, a bell crank lever pivoted to said frame, with one arm extending substantially horizontal and another arm depending therebelow, a transmission link connecting the substantially horizontal arm of said lever to an intermediate portion of said eccentric rod, and a valve rod connecting the depending arm of said lever to said valve, to operate the latter, the point of connection of the transmission link to the eccentric rod being close to the point of suspension of said rod from said reversing member link means, whereby the valve movement due to the fall and rise of the frame with respect to the main crank pin when the locomotive is going around curves is minimized and satisfactorily allowed for.

5. In a steam-engine valve gear, in combination with a frame and a valve, valve-actuating mechanism, and reversing mechanism for said actuating mechanism comprising a yoke, a link fixed to the top of said frame, a block carried by said yoke and slidable in said link, said yoke having normally depending end portions carrying blocks vertically reciprocable in said frame, and radius arms to said actuating mechanism, carried by intermediate portions of said yoke.

6. In a steam-engine valve gear, actuating mechanism for the valve comprising linkage including an eccentric rod moved solely by connection with the main crank pin and supported on a frame intermediate said pin and valve, and a reverse yoke carrying a block slidable in a link fixed to the top of said frame, said yoke having normally depending end portions carrying blocks vertically reciprocable in said frame, radius arms the upper ends of which are pivotally carried by intermediate portions of said yoke and the lower ends of which are pivotally connected to the free end of said eccentric rod.

7. In a steam-engine valve gear, in combination with a gear frame, a main crank pin and a valve, an eccentric crank secured to said pin and with its free end trailing it 90° in forward motion, an eccentric rod, one end of which is pivoted

to said free crank end, a reverse yoke carrying a block slidable in a link fixed to the top of said frame, said yoke having normally depending end portions carrying blocks vertically reciprocable in said frame, radius arms the upper ends of which are pivotally carried by intermediate portions of said yoke and the lower ends of which are pivotally connected to the free end of said eccentric rod, a bell crank lever pivoted to said frame and with one arm extending substantially horizontal and another arm depending therebelow, a transmission link with its lower end pivoted to said eccentric rod near its front end and its upper end pivoted to the free end of said substantially horizontal bell crank arm, and a valve rod with its rear end pivoted to the free end of said depending bell crank arm and its front end pivoted to said valve for operating it.

8. In a steam-locomotive valve gear, in combination with a frame, a main crank pin and a valve, an eccentric rod, one end of which is pivoted with respect to a point substantially 90° out of phase, but movable with said crank pin, a reversing member having an upper end portion to which operating means is connected, and bifurcations extending downwardly therefrom, straddling portions of said frame, and with lower end portions movably connected to said frame portions, links connecting portions of said member intermediate its upper and lower end portions to the other end of said rod to cause it to swing in an arc about a center determined by the setting of said member, a bell crank lever pivoted to said frame, a transmission link connecting one arm of said lever to an intermediate portion of said eccentric rod, and a valve rod connecting another arm of said lever to said valve, to operate the latter, the point of connection of the transmission link to the eccentric rod being close to the point of suspension of said rod from said reversing member links, whereby the valve movement due to the fall and rise of the frame with respect to the main crank pin when the locomotive is going around curves is satisfactorily minimized and allowed for.

9. In a steam-engine valve gear, actuating mechanism for the valve comprising a frame, an arcuate link fixed to said frame, a reversing member, a block carried thereby and slidable in said link, means for moving said member, an eccentric crank, an eccentric rod coupled thereto at one end, a link movably supporting the other end of said rod from a part of said reversing member below said carried block, and means operatively connecting an intermediate portion of said rod to said valve.

10. In a steam-engine valve gear, actuating mechanism for a valve comprising a frame, an arcuate link fixed to said frame, a reversing member, a block carried thereby and slidable in said link, a portion of said member normally depending below said block being mounted to reciprocate with respect to said frame as the member oscillates, means for moving said member, an eccentric crank, an eccentric rod coupled thereto at one end, means movably supporting the other end of said rod from said reversing member, and means operatively connecting an intermediate portion of said rod to said valve.

11. In a steam-engine valve gear, actuating mechanism for the valve comprising a frame, an arcuate link fixed to said frame, a reversing member, a block carried thereby and slidable in said link, means for moving said member, an eccentric crank, an eccentric rod coupled thereto at one

end, link means movably supporting the other end of said rod from a part of said reversing member beneath said link, a bell crank pivoted to said frame, means connecting an intermediate portion of said rod to one arm of said crank, and means operatively connecting the other arm of said crank to said valve.
